UNITED STATES PATENT OFFICE.

RICHARD F. SPAMER, OF NEW YORK, N. Y., ASSIGNOR TO WESTERN ELECTRIC COMPANY, OF NEW YORK, N. Y., A CORPORATION OF ILLINOIS.

SIGNALING SYSTEM FOR PARTY-LINES.

1,071,652.

Specification of Letters Patent. Patented Aug. 26, 1913.

Application filed September 15, 1910. Serial No. 582,247.

To all whom it may concern:

Be it known that I, RICHARD F. SPAMER, citizen of the United States, residing at New York, in the county of Westchester 5 and State of New York, have invented a certain new and useful Improvement in Signaling Systems for Party-Lines, of which the following is in full, clear, concise, and exact description.

10 My invention relates to signaling systems for use with party line selective systems and more particularly to a system wherein a plurality of party telephone lines extending from a single station are arranged to receive 15 signaling current from a single source or signaling apparatus.

In the class of party line systems known as train-despatching systems to which this invention is particularly applicable each 20 line is provided with a plurality of selecting devices one at each station, arranged to act in response to impulses from a central or sending station to operate a signal or other device at the corresponding station, each 25 station on a line requiring a different number or character of impulses from the sending station to operate or permit the operation of the signal. The impulses may be sent over the line by apparatus comprising 30 an impulse relay which acts in response to a toothed impulse wheel to open and close a battery circuit onto the line. There may be an individual sender for each station on each line, or a sender for each line provided 35 with means for regulating at will the number of impulses sent out for signaling purposes.

In accordance with my invention the apparatus at the sending station is so arranged 40 that when a sending key is operated the line with which that key is associated will be automatically connected with the contacts of the impulse-transmitting relay, and will be disconnected therefrom when the call is 45 completed. This is preferably accomplished by providing for each line a line relay the magnet whereof is in a circuit with the magnet of the impulse relay and is controlled by the sending keys associated with 50 that particular line, the line relay when operated being adapted to close contacts which connect the line with the impulse circuit.

One of the advantages resulting from 55 this arrangement is that the impulse relay and the line relay are operated automatici-

cally with the operation of the sending key, thus accomplishing all switching operations automatically. Another advantage is that the sending apparatus is cut off from the line during the use of the telephones thus 60 eliminating from the talking circuit apparatus which would be detrimental to the transmission of voice currents.

The accompanying drawing is a diagram of the apparatus and circuits which I prefer to employ.

In said drawing the circuits and apparatus are shown as arranged for signaling upon three lines, although the number of lines may vary within reasonable limits.

70 In the drawing 3, 4 and 5 designate line circuits across each of which are bridged substations 6, 6, each of which will be equipped with a selector as usual in systems of this type. For each of the lines 3, 4 and 5 there is provided a line relay 7 having two contact levers 8 and 9 which when closed connect the corresponding line with an impulse-transmitting or signaling circuit as will hereinafter appear. The contact levers 8 may be electrically connected or strapped together in one group and the levers 9 in one group, the two groups being connected to opposite sides of the signaling circuit. 75 For each line there is shown a set of sending keys 12, each key comprising a toothed impulse wheel 13 and a contact spring 14 adapted to be engaged by the teeth of a co-operating impulse wheel. An adjustable segmental plate 15 is shown on each of the 80 wheels for regulating the number of teeth which will pass under the contact spring 85 for signaling purposes. The contact springs for each set of sending keys are strapped together and all of the sets are connected to one pole of a battery 18. The impulse wheels of each set of sending keys are also strapped together, but each set is individually connected to one terminal of the winding of its corresponding line relay.

100 Referring now to the apparatus employed for applying signaling current to the line, this is shown as embracing a relay 20 adapted when energized to close contacts 21, 21 which are connected with opposite poles of a battery 22. Armatures 23 and 24 of said relay are connected respectively with the strapped contact levers 8 and 9 of the line relays 7, the connection being through the 105 windings of retardation coils 25 and 26; the 110

object of the retardation coils being to smooth down the current impulses so that disturbing noises will not be caused in the telephones in case conversation is being carried on over the line. A condenser 27 bridged across the lines between said retardation coils assists in smoothing the impulses and absorbing inductive discharges. A shunt path comprising a condenser 28 10 and a non-inductive resistance 29 is bridged around each contact lever and contact of the impulse relay, in order to prevent excessive sparking at the contacts when the circuit is opened and closed. Each of the lines 3, 4 15 and 5 is connected through a set of condensers 30, 30 with a train despatcher's line 31 leading to a despatcher's telephone set 32.

The operation is as follows: Assuming 20 that it is desired to call a party on line 3 the despatcher or operator at the sending station will start one of the impulse wheels 13 associated with that line to rotating. The engagement of the teeth of the impulse 25 wheel 13 with the spring contact 14 will complete a circuit through the line relay 7 associated with the line 3 and the impulse relay 20. This circuit may be traced from one side of battery 18 through conductor 35, conductor 36, the contact spring 14, impulse 30 wheel 13, conductor 37, winding of the line relay 7 associated with line 3, conductor 38, conductor 39, winding of impulse relay 20 and conductor 40 to the other side of the battery 18. Current from the battery 18 35 over the circuit traced will energize the line relay 7 and the impulse relay 20 causing the operation of the contact levers of both relays. The operation of these contact levers will complete a path for current which may 40 be traced from one side of battery 22, through conductor 45, one of the contacts 21 of the impulse relay 20, windings of the retardation coils 25 and 26, conductor 46, conductor 47, contact 48 of the line relay, over 45 one conductor of the line 3 through the way-stations 6, 6 on said line and back over the other conductor of said line 3, through contact 49 of the line relay, conductor 50, conductor 51, the other windings of the retardation coils 25 and 26, the other contact 21 of 50 the impulse relay 20 and conductor 52 to the other side of battery 22. Each line relay 7 is provided with a copper shell 55 around its core to make it slow-acting as compared 55 with the impulse relay 20 so that it will not fall back during the intervals between the successive current-impulses caused by the impulse wheel making and breaking the circuit through the line and impulse relay first 60 described. The impulse wheel 13 will cause impulses to be sent over the line until the segmental plate 15 thereon comes into engagement with the contact spring, whereupon the circuit will be continuously closed 65 through the winding of the impulse relay 20

and current from the battery 22 thus maintained upon the line during the time that the segmental plate is passing under the contact spring 14. This current may operate a signal at the called station in a well known way. When the segmental plate and all of the teeth of the impulse wheel have passed under the contact spring 14 the circuit through the impulse and line relays will be opened and that particular line will be disconnected from the signaling circuit leaving the signaling apparatus free for use on another line. 70

It will be noted that the line 31 leading to the despatcher's telephone is connected to the train lines outside the contacts of the line relays, so that during the time conversation is going on between the despatcher and a waystation on any line, that line will be disconnected from the current impulse 85 apparatus, thus removing the retardation coils from the talking circuit. 80

The condensers 30 are interposed between the lines leading to the train despatcher's telephone and the train lines to prevent the 90 impulses which are sent out to signal a party on one line from affecting the selectors of the other lines extending from the same station. 95

I claim:—

1. The combination with a plurality of lines extending from one station, of current impulse apparatus at said station for signaling over said lines, operating mechanism for said current impulse apparatus individual to each of said lines, and means operating automatically with the operation of said mechanism to associate said impulse apparatus with its corresponding line. 10

2. The combination with a plurality of 10 lines each having selective devices connected thereto, of an impulse relay, a line relay for each line adapted to extend the circuit of said line to the contacts of said impulse relay, a sending key for each line, a circuit for 11 said impulse relay arranged to be controlled by any of said sending keys and means brought into action in the operation of the sending key of any line for operating the line relay of such line. 11

3. The combination with a plurality of lines each having a selective device connected thereto, of an impulse relay, a line relay for each line adapted to extend the circuit of said line to the contacts of said 12 impulse relay, circuits common to said impulse relay and each of said line relays, and a sending key for each line adapted in its operation to close the circuit through the winding of said impulse relay and the line 12 relay of such line. 12

4. The combination with a plurality of lines extending from one station, of signaling apparatus at said station for signaling on any one of said lines, switching devices 13

individual to each of said lines, said switching devices operating to associate said signaling apparatus with its line for purposes of signaling and to disconnect it therefrom 5 when the signaling is completed and circuit closing devices at said station controlling jointly the operation of said signal apparatus and said switching device.

5. The combination with telephone lines 10 each having waystations connected therewith, each waystation including telephone apparatus and a selective signaling device, of means for operating said signaling devices embracing an impulse relay, retardation coils in circuit with the contacts of said 15 relay and a condenser in bridge of the circuit containing said retardation coils.

6. The combination with telephone lines each having selective signaling devices con-

nected therewith and a telephone set connected with all of said lines, of an impulse relay for operating said signaling devices, retardation coils in circuit with the contacts of said impulse relay, a condenser in bridge of the circuit containing said retardation coils, switching means individual to each line adapted to extend the circuit of such line through the retardation coils to the contacts of said impulse relay for purposes of signaling and to disconnect it 20 therefrom when the signaling is completed. 25

In witness whereof, I, hereunto subscribe my name this 14th day of Sept. A. D., 1910.

RICHARD F. SPAMER.
